SOOT ERADICATOR

Filed May 26, 1924

2 Sheets-Sheet 2

UNITED STATES PATENT OFFICE.

GEORGE L. HESS, OF INDIANAPOLIS, INDIANA.

SOOT ERADICATOR.

Application filed May 26, 1924. Serial No. 716,036.

To all whom it may concern:

Be it known that I, GEORGE L. HESS, a citizen of the United States, residing at Indianapolis, in the county of Marion and 5 State of Indiana, have invented certain new and useful Improvements in Soot Eradicators, of which the following is a specification.

My said invention relates to a soot eradicator the principal purpose of which is to remove soot from smoke in an efficient manner thereby reducing the smoke nuisance particularly in cities and manufacturing districts and to realize profit from the preservation and sale of the by-product as a coloring 10 matter.

Referring to the accompanying drawings which are made a part hereof and on which similar reference characters indicate similar parts,—

20 Figure 1 is an elevation of my device, Figure 2, a section on line 2—2 of Figure 1, Figure 3, a section on line 3—3 of Figure 1, 25 Figure 4, a section on line 4—4 of Figure 5,

Figure 5, a central vertical section of the device at right angles to the plane of Figure 1, 30 Figure 6, a section on line 6—6 of Figure 5, and Figure 7 a section on line 7—7 of Figure 5.

In the drawings reference character 10 indicates a casing adapted to be mounted in or on a smoke pipe or stack or in or on a device connected to such smoke pipe or stack in such a manner that the smoke can be caused to pass through said casing. At any 35 convenient distance from the bottom of the casing a transverse support is provided, this support having an uninterrupted central portion 11 providing a deflector for protecting the parts above the same from the direct 40 action of the heat from the fire and having radial arms 12 secured to the casing in any convenient manner. At the center of the deflector there is a step bearing 13 supporting an upright shaft 14 journaled at its 45 upper end in tubular bearing on a cruciform support 15. The shaft carries a lower fan

16, an upper fan 17 and an upper deflector 18 preferably consisting of a relatively small cap of sheet metal preventing passage of smoke through the central part of the 55 casing and a larger convex cap of wire screen through which the smoke may pass with some retardation. The outer periphery of the larger cap is spaced from the wall of the casing so that the residue of the 60 smoke can pass freely between such periphery and the wall. A screen mill 19 corresponding in form to the casing and therefore ordinarily tubular has a closed end 20 also of wire screen through which the shaft 65 14 passes. The screen mill is closed at the bottom by a floor 21 of wire screen which has an opening of sufficient size to receive the fan 16 as shown. Beneath the lower fan or if desired beneath each fan there are pipes 70 22 providing for the passage of fresh air into the screen mill as a means of cooling the mill and its content and of purifying the soot-laden gases above said pipes, thereby increasing the weight of the content and the 75 retardation incident thereto.

A motor 23 is mounted outside the casing and serves to drive a shaft 24 connected by bevel gearing 25 and 26 to drive the shaft 14. Said motor may be an electric motor, a 80 spring motor or any other preferred form of motor and may be controlled by means of a cord shown at 27. The shaft 24 also carries a pulley 28 driving a belt 29 the use of which will appear hereinafter.

In some cases the mechanism heretofore described will be insufficient for satisfactory removal of the soot and in such cases I provide means which may remain idle except when needed and which if needed acts subsequently to the screen mill hitherto described for further removal of small and light particles of soot. Such mechanism comprises a heavy cap 30 pivoted at 31 on the casing and provided with a cord 32 for 90 moving it on its pivot. Said cap is normally kept raised as indicated in the dotted line position of Figure 5 but when the auxiliary mechanism above referred to is to be put in use the cap is lowered to the full 100 line position whereupon the smoke ceases to pass directly upward out of the casing and

follows the line indicated by arrows at the right hand side of Fig. 5, passing down through a conduit 33 to a casing 34 and thence out through a conduit 35 back to the 5 upper end of the casing 10.

The casing 34 is in effect a tank supported on a bracket 36 secured in any convenient manner to the upright casing 10. A quantity of water or other suitable material, preferably liquid, is held in the lower part of the tank and a shaft 37 is journaled in the casing which shaft is here shown as being above the level of the water though this need not necessarily be so. The shaft 15 is driven by the belt 29 passing over a pulley 37 and it carries a plurality of circular screens 38 secured to the shaft in any convenient manner said screens having their outer periphery protected by means of rings 39 fixed to the wire screens and lying close to the wall of the circular casing.

It will be evident from the above description that smoke normally passing directly through the casing 10 will be deflected and 25 slightly delayed by the deflector 13 after which the fans will act centrifugally to produce currents passing through the walls of the tubular screen. This action will interrupt the direct upward course of the smoke 30 and thus cause some of the heavier particles of soot to fall back toward the bottom of the casing. Other particles will be caught by the screen and may then adhere thereto for a time or also fall back. This action 35 is further assisted by the deflector 18 and after passing this deflector the smoke which has been purified to a considerable extent may then go on out of the chimney in ordinary manner. If the smoke is very dense 40 or if there is serious objection to soot in a particular locality I may pass the smoke through the tank in which the screen fans 38 are then turned by means of the shaft 37. If the screens are wet they will act more 45 effectively to sift out all soot in the smoke and by reason of their revolving action they will pass through the water at each rotation and be washed to free them of soot, the water, of course, being drawn off at proper 50 intervals and fresh water supplied.

The soot may be removed by any suitable means either manually or automatically, and may thereafter be treated in various ways, as by refining, filtering, etc., to prepare it for market, in the form of lampblack for use as an ingredient of paint and printers' ink and for other purposes well known to those skilled in the industrial arts.

It will be obvious to those skilled in the art that various modifications may be made in my device without departing from the spirit of the invention and therefore I do not limit myself to what is shown in the drawings and described in the specification 60 but only as indicated in the appended claims.

Having thus fully described my said invention, what I claim as new and desire to secure by Letters Patent, is:

1. A soot eradicator comprising a tubular screen located in position to receive smoke, 70 and fans within the screen for forcing the smoke radially outward through its walls, substantially as set forth.

2. A soot eradicator comprising a tubular screen located in position to receive smoke, 75 said screen being closed at its upper end by screen material, and one or more fans within in the screen for forcing the smoke out through the walls and the tops, substantially as set forth.

3. A soot eradicator comprising a tubular screen located in position to receive smoke, 80 said screen being closed at its upper end, means within the screen for forcing the smoke through its walls, and a deflector below the screen for protecting it from the direct heat of the fire, substantially as set forth.

4. A soot eradicator comprising a tubular screen located in position to receive smoke, 90 said screen being closed at its upper end, means within the screen for forcing the smoke through its walls, a deflector below the screen for protecting it from the direct heat of the fire, a shaft having a step bearing 95 in said deflector said shaft extending up through the screen, and means on the shaft to force the smoke through the sides of the screen, substantially as set forth.

5. A soot eradicator comprising a tubular screen located in position to receive smoke, 100 said screen being closed at its upper end, one or more fans within the screen for forcing the smoke out through the walls, and means for admitting fresh air into the 105 screen adjacent to said fans, substantially as set forth.

6. A soot eradicator comprising a casing, a tubular screen located in position to receive smoke, said screen being closed at its upper end, a shaft extending axially of the screen, one or more fans driven by said shaft, and a deflector secured to the shaft above the screen to force the smoke toward the walls of the casing, substantially as set 115 forth.

7. In a soot eradicator, a dry screen mill through which the smoke passes, means adjacent thereto for washing the smoke and controlling means whereby the smoke may 120 be caused to pass through the washing means, substantially as set forth.

8. In a soot eradicator, a dry screen mill through which the smoke passes, a tank adjacent thereto through which the smoke may pass said tank being circular in vertical section, a shaft located axially of the tank, screens on said shaft, and means for rotating the screens for cleaning them, substantially 125 as set forth.

9. In a soot eradicator, a dry screen mill through which the smoke passes, a casing enclosing the screen-mill, a cap in the casing beyond said screen-mill, a conduit through 5 which the smoke passes when the cap is closed, a tank forming part of said conduit, means in said tank for screening the smoke passing therethrough, and a body of liquid

in the tank for washing said screening means, substantially as set forth. 10

In witness whereof I have hereunto set my hand at Indianapolis, Indiana, this 17th day of May, A. D. nineteen hundred and twenty-four.

GEORGE L. HESS.
